[57] CLAIM

The ornamental design for a keycap assembly with extended sidewall integrated pointing stick for typing and pointing operations in a computer keyboard, as shown and described.

DESCRIPTION

FIG. 1 is a perspective view of the keycap assembly with extended sidewall integrated pointing stick according to my invention;

FIG. 2 is a front view of the keycap assembly of FIG. 1; FIG. 3 is a right side view of the keycap assembly of FIG. 1;

FIG. 4 is a rear elevational view of the keycap assembly of FIG. 1;

FIG. 5 is a top view of the keycap assembly of FIG. 1 shown disposed in a computer keyboard wherein the surrounding keys are shown in broken lines for illustrative purposes only and form no part of the claimed design; and,

FIG. 6 is a bottom view of the keycap assembly of FIG. 1.
